UNITED STATES PATENT OFFICE.

LEOPOLD S. SAMUEL, OF NEWARK, NEW JERSEY.

REINFORCED PAD FOR SHOES.

1,194,428. Specification of Letters Patent. Patented Aug. 15, 1916.

Application filed September 6, 1912. Serial No. 718,823.

To all whom it may concern:

Be it known that I, LEOPOLD S. SAMUEL, a citizen of the United States, residing at Newark, in the county of Essex and State 5 of New Jersey, have invented certain new and useful Improvements in Reinforced Pads for Shoes; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

15 This invention relates to an improved pad for shoes that is placed on the bottom of a shoe to form a cushion so that the walking of the person is with less shock than when the shoes are without the pads.

20 The invention is further designed to provide a pad that can be applied to a spot where the wearer wears out the shoe quickest, and in this way the shoes are made to last longer.

25 The pad is made up of a body portion which is somewhat resilient and is provided at its edges with a layer or edging, and in some instances, with a set of separated spots, of material that will resist wear more than 30 the body portion of the pad. In this way the life of the pad is prolonged while its resiliency or compressible qualities are not disturbed.

The pad is easily made and its construction is such that it can be cheaply made.

The invention is illustrated in the accompanying drawing, in which—

Figure 1 is a view showing a receptacle holding the wearing mixture with a set of 40 pads being dipped therein to give the pads a coating on the edge. Fig. 2 is a face view of one of the pads after it is coated, and Fig. 3 is a section of Fig. 2. Fig. 4 is a detail section with the mixture applied to both a 45 perforation and the edge. Fig. 5 is a view of a straight strip for heels or soles with notches in one edge filled with the wearing mixture. Fig. 6 is a heel pad notched and then supplied with wearing mixture. Fig. 50 7 is a section of Fig. 6.

The pad has a body portion 10 which is of resilient material, such as rubber, felt, in fact any material suitable for the purpose

of giving a soft or cushion tread when walking.

In Fig. 1 I show the pad in the shape of a heel pad. The body portion is in the form of a sheet or layer, and these are placed side by side and then dipped, as in Fig. 1, into a mixture 11 which, when dry, becomes hard 60 and resists wear. When the pads 10 are separated, the mixture forms a hard edge 12 to prevent a quick wearing out of the pad, but is not sufficient in area to affect appreciably the resiliency of the pad. The mixture which is applied to the pad can be composed of a number of ingredients and is preferably made up of a binding agent to adhere 65 to the pad and also one to hold a hard or good wearing substance. Such mixtures may be used as cement and sand, cement alone, cement and metal filings, cement and gravel, cement and carborundum, cement and hair or cotton waste, glue and sand, in fact any hard gritty substance along with a cementitious or mucilaginous material which will 70 dry hard and secure itself to the pad.

In Fig. 4 I show the perforation and also the adjacent edges of the pad covered with the wear-resisting material.

In Figs. 6 and 7 is a pad notched at its edges, the notches 15 being widest at their outer edges and filled with wear-resisting material 16.

I sometimes employ straight pads on heels 85 or soles, such as the pad 17 in Fig. 5, which has filled notches 18, the filling being of wear-resisting material.

In these pads it will be noticed that both sides are alike and the affixing of them to the 90 shoe is facilitated, as the person applying them need only fasten them, on either face, by either nails, screws, adhesive or any other fastening means.

Having thus described my invention, what 95 I claim is:—

1. As an article of manufacture, a shoe pad comprising a body portion of cushion material of substantially the same thickness, the edge of the body portion being provided 100 with a non-resilient wear-resisting gritty material.

2. As an article of manufacture, a flat sheet of cushion material having an edge portion made up of a binding agent and a 105 gritty substance.

3. As an article of manufacture, a body portion of cushion material, said body portion being of substantially the same thickness throughout, and an edge section formed of a gritty substance mixed with a binding agent to hold the substance in a mass and to cause it to adhere to the body portion.

In testimony, that I claim the foregoing, I have hereunto set my hand this 3rd day of September 1912.

LEOPOLD S. SAMUEL.
